UNITED STATES PATENT OFFICE.

ARTHUR B. MODINE, OF RACINE, WISCONSIN.

RADIATOR.

Application filed December 29, 1923. Serial No. 683,402.

To all whom it may concern:

Be it known that I, ARTHUR B. MODINE, a citizen of the United States, residing at Racine, in the county of Racine and State of Wisconsin, have invented certain new and useful Improvements in Radiators, of which the following is a description.

My invention belongs to that general class of devices known as radiators and more particularly to an improved cooling system and radiator, the same being particularly adapted for use on automobiles and like vehicles.

The invention has among its objects the production of a device of the kind described, which is simple, efficient, reliable, compact, and a satisfactory cooling system and radiator for use wherever found applicable. More particularly it has as an object the production of a radiator for use on automobiles and like vehicles for cooling an internal combustion engine and which will permit the engine to be run at a temperature to maintain a high efficiency in the winter or in cool weather as well as in warm weather. It also has as an object the production of a radiator which will conserve the anti-freeze mixtures generally employed in cold weather and prevent their dissipation or loss by evaporation.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts:

Fig. 1 is a side elevation of my improved device applied to an internal combustion engine;

Fig. 2 is a top elevation of the same;

Fig. 3 is a front elevation of the radiator;

Fig. 4 is a sectional view taken substantially on line 4-4 of Fig. 3; and

Fig. 5 is a view in elevation of one type of shutter that may be employed.

In the cooling systems employed on automobiles or the like, or in connection with internal combustion engines, the system is made adapted for wide ranges of temperature, and while the engine may operate at a temperature to give high efficiency in warm

weather, the same does not give the same efficiency in cold weather unless the radiator is more or less covered, thereby reducing the cooling effective area. Generally in the winter it is customary for the operator to replace the usual cooling medium, such as water with a non-freezing solution, as for example a mixture of water and alcohol or the equivalent. Obviously, when alcohol is added, the boiling point is lowered, and frequently they add glycerine to the mixture to raise the boiling point. The radiator is usually more or less covered in the winter, and it is not uncommon for the mixture to boil or reach a fairly high temperature, before partially uncovering, in which case the efficiency of the anti-freeze mixture is affected by the evaporation of the alcohol. The result is that the driver in endeavoring to save his alcohol from evaporating and to maintain a mixture of sufficient strength to prevent freezing, will apply his covering to the radiator in such a manner as to operate the engine at a lower temperature, thereby decreasing the efficiency of the engine. With the present invention or system, the radiator is so designed that the system and radiator operate in the summer or during warm weather substantially in the normal manner with proper efficiency of the engine. In the winter, however, the temperature may be maintained so as to give the same efficiency without danger of loss of the anti-freeze mixture as the same

may boil or become vaporized but is condensed and returned to the system without material loss. The system, therefore, not only operates so as to give the greatest efficiency to the engine, but it also is at all times safe against freezing up.

Means are also provided, as will be described, to provide a control for the temperature whereby the engine is prevented from becoming too hot or the cooling medium being evaporated at a rate greater than the condenser can take care of the same.

Referring to the drawings, 1, 2 and 3 represent what may be termed water tanks, which are connected by the cores 4 and 5. The tanks may be of the desired size and shape, as may also the cores, and it may be mentioned that the cores may be of the tubular type or cellular type or any equivalent construction. As illustrated, 6 represents an internal combustion engine, a compressor or any other apparatus which is to

be cooled, 7 representing one of the conduits from tank 1, 8 a pump arranged where desired in the system, and 9 a conduit extending to the tank 2. There are also conduits 5 or tank 2. The shutters are shut so as to partially or entirely shut off the air going through the core 4. When the engine is operated, it quickly heats up the fluid in the system, thereby permitting the engine to quickly heat up to its greatest efficiency and to continue operating at high efficiency. Any vapors driven off from the tank 3 and core 4, owing to the high temperature, will pass up into the core 5 and to tank 2. However, with the air, particularly the cold air of winter, passing through the core 5, this causes an immediate condensation of the vapors in the core 5 which drains back into the core and is thereby taken up again in the system and circulated through the engine.

10 understood that such details of construction may be varied as desired. I have shown the upper tank provided with the usual filling spout 14. The installation shown is more particularly that employed on an automobile 15 for cooling a gas engine. I have shown the lower core 4 provided with a shutter means so that when desired this portion of the radiator may be partially or entirely covered. While any type of shutter may be used, that 20 shown is comparatively simple and satisfactory.

Referring particularly to Figs. 4 and 5, 15 and 16 represent shutters provided with the openings 17 and 18. When either one of 25 the shutters is moved relative to the other, the openings are brought into registry so as to provide an opening of the desired size through which air may pass so as to pass through core 4. The shutter may be controlled or operated manually or automatically, either by thermostatic means or pressure controlled means, but the manual means being most simple, I have not shown in detail the automatic mechanism.

30 The upper tank 2 may be provided with the usual overflow pipe 19, and it may be also provided with a pressure relief device 20 to prevent the pressure in the system from rising above a predetermined degree. The conduits 11 are also shown provided with valves 21, which may be of any suitable type. I have also shown a valve 22 for controlling 35 the flow of the medium through pipe 9.

In describing the operation of the device, 40 it may be mentioned that in the summer time the shutters may be and are generally omitted, or at least kept open. Valves 21 and 22 are so operated that the circulation from the water jacket of the engine or the like is 45 through pipe 9 into the tank 2 and thence through the radiator and pipe 7 back through the pump to the engine. In this case, the system is filled up with water or the like, filling the cores and substantially all of 50 the tanks. The circulation is through the radiator substantially in a normal manner as is the case in any radiator. As the heated medium passes through the radiator, its heat is dissipated and taken up by the air drawn 55 through the radiator by the fan 12 or the equivalent. In the winter time or in cold weather, valve 22 is closed and valve 21 60 opened and the water level in the system brought substantially to the height of the tank 3 without the medium being in the core

5 or tank 2. The shutters are shut so as to partially or entirely shut off the air going through the core 4. When the engine is operated, it quickly heats up the fluid in the system, thereby permitting the engine to quickly heat up to its greatest efficiency and to continue operating at high efficiency. Any vapors driven off from the tank 3 and core 4, owing to the high temperature, will pass up into the core 5 and to tank 2. However, with the air, particularly the cold air of winter, passing through the core 5, this causes an immediate condensation of the vapors in the core 5 which drains back into the core and is thereby taken up again in the system and circulated through the engine.

10 This condensation assists in keeping the temperature of the medium down and yet does not bring the temperature in the system down to a point where the efficiency of the 15 engine is affected. In case of excessive pressure on the radiator, this may be relieved at the vent 20 which is normally closed except when the pressure reaches a predetermined amount. It is obvious that there will be no 20 loss of alcohol or anti-freeze solution in case the temperature of the cooling medium reaches or passes the boiling point as the same will be immediately re-condensed and returned to the system without loss. The 25 pressure referred to may be utilized to control the shutter, but as before mentioned, I have not considered it necessary to illustrate this herein.

The system illustrated has many advantages, the most important being the increased efficiency of the engine in the winter, including a smoother running engine, a saving in gas and oil, as well as continuous protection of the cooling system from freezing 100 by maintaining a satisfactory mixture and preventing a loss of the mixture.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a device of the kind described and in combination, a radiator provided with upper and lower tanks and a core connecting the same, one of said tanks provided with an inlet and the other with an outlet for the circulation of a fluid medium, a condenser arranged to receive, condense and return vapors discharged from the system, and means for closing said inlet to direct the fluid through the condenser.

2. A cooling system for fluid cooled combustion engines comprising a condenser operatively connected to receive the vapors

from the cooling fluid and condense and return the same to the system, and adjustable means whereby the fluid may be directed through the condenser.

5 3. In a device of the kind described and in combination, a radiator provided with a condenser arranged in proximity to the radiator and operatively connected therewith whereby vapors discharged from the 10 radiator are condensed and returned to the radiator, and means for causing the fluid to flow through the condenser.

4. A radiator comprising two tanks communicating with each other and constructed 15 for the cooling of fluid flowing from one tank to the other, one tank having an inlet and the other an outlet for the admission and discharge of the cooling fluid, a third tank mounted above one of the first-mentioned 20 tanks and communicating therewith and provided with a core connecting the same therewith, said core provided with means for dissipating heat units from the contents thereof, said third tank having an inlet, and means for controlling the flow of the fluid through said last-mentioned inlet.

5. In a cooling system, a radiator provided with a plurality of superimposed tanks, air-cooled connecting means between 30 the tanks, means containing fluid to be cooled a conduit extending from the lower tank and communicating with the fluid-containing means, a branched conduit extending from the liquid-containing means to the two upper tanks, means for controlling the passage of fluid through said branched conduit in a predetermined manner, means for causing a flow of air through said cores, and means for normally preventing the circulation of air through the core connecting the lower and intermediate tank.

40 6. In a device of the kind described for internal combustion engines, an air-cooled radiator comprising a radiator having upper and lower tanks, a core arranged between said tanks and provided with an in-

termediate tank communicating with the upper and lower tanks through said core, conduits connecting the upper and intermediate tank with the engine jacket and a 50 conduit connecting the lower tank with the engine jacket, means for controlling the fluid passing through said first-mentioned conduits in a predetermined manner, means for causing a circulation of air through said cores, means preventing a circulation of air through the core connecting the lower tank and intermediate tank as desired, means for preventing excessive pressures in a system, and means for causing a circulation of a 60 fluid cooling medium through the system.

7. In a device of the kind described for internal combustion engines, an air-cooled radiator comprising a radiator having upper and lower tanks, a core arranged between said tanks and provided with an intermediate tank communicating with the upper and lower tanks through said core, conduits connecting the upper and intermediate tank with the engine jacket and a conduit 70 connecting the lower tank with the engine jacket, and means for controlling the fluid passing through said first-mentioned conduits in a predetermined manner.

8. In a device of the kind described for internal combustion engines, an air-cooled radiator comprising a radiator having upper and lower tanks, a core arranged between said tanks and provided with an intermediate tank communicating with the upper and lower tanks through said core, conduits connecting the upper and intermediate tank with the engine jacket and a conduit connecting the lower tank with the engine jacket, means for controlling the fluid passing through said first-mentioned conduits in a predetermined manner, and means for causing a circulation of air through said cores.

In testimony whereof, I have hereunto 90 signed my name.

ARTHUR B. MODINE.
